UNITED STATES PATENT OFFICE.

ANTONIO BORRÁS AND FERNANDO IRIARTE, OF BUENOS AIRES, ARGENTINA.

ROTARY PUMP.

1,241,704.

Specification of Letters Patent.

Patented Oct. 2, 1917.

Application filed March 1, 1916. Serial No. 81,319.

To all whom it may concern:

Be it known that we, ANTONIO BORRÁS and FERNANDO IRIARTE, citizens of the Republics of Portugal and Argentina, respectively, and both residents of the city of Buenos Aires, Argentina, have invented certain new and useful Improvements in Rotary Pumps, of which the following is a specification.

10 The invention relates to an improvement in rotary pumps and has as its object the provision of such device which will be efficient, of great power and capable of easy reversibility.

15 In the following we have described, in connection with the accompanying drawings, a device illustrating one way of carrying out our invention, the features thereof being hereinafter more particularly set 20 forth in the claims.

In the drawings Figure 1 is a longitudinal, vertical, sectional view of one form of our invention and Fig. 2 is a vertical cross-sectional view of the same along the line 25 A—B of Fig. 1.

Similar numerals of reference indicate similar parts throughout the several views.

1 indicates a fixed shaft eccentrically mounted in brackets 2, 2 with reference to 30 casing 3. 4, 4 indicate plates forming the top and bottom of the casing. 5 and 6 indicate the end walls of the inner chamber rotatably mounted in ball-bearings 7 and 8 respectively in the casing 3 and eccentric to 35 shaft 1. 9 indicates a pulley carried by end wall 6 adapted to be driven by a belt from any suitable source of power (not shown). 10 indicates a frame bolted to end walls 5 and 6. Frame 10 is shown as provided with a plurality of tubular chambers 40 11, 11, here shown as twenty four in number, in sets of three across the face of the frame 10 and in sets of eight circumferentially thereof. Each of said chambers 11 is 45 provided with a plunger 12, each plunger excepting one being pivotally connected to a connecting rod 13 in turn pivotally connected at its other end to a plate or socket 14 revolvably mounted on shaft 1. The remaining plunger or set of plungers is pivotally connected to an arm 15 integral with or fixedly connected to plate or socket 14.

50 We have shown the connecting rods 13 for each set of three plungers extending in parallel across the face of the frame 10 as brought together to a common pivotal point

on plate or socket 14 (Fig. 2), so that all the plungers of each set will operate in unison. Connecting rods 15 are similarly brought to a common point on plate or 60 socket 14. 16, 16 indicate shutters or vanes extending cross the face of the frame and each adapted to completely cover one set of tubular chambers 11. Shutters 16 are carried by rockable shafts 17 journaled in casing 3 and carrying crank arms 18 at one end. Crank arms 18 are connected by a link 19. Handle or lever 20 is mounted on one of shafts 17 and is adapted to rock the other shaft 17 through crank arms 18 and link 19 70 so as to rock shutters 16 to cause them to assume the position shown in Fig. 1 or the opposite thereof. Shutters 16 are shaped to conform to the periphery of frame 10 so that when in the position shown in Fig. 1 in 75 connection with shoulders 21 in wall 3 they will act as a closure against water or other fluid returning from discharge 22 to inlet 23.

It will be noted that the passage 23 extends about the openings of but three of the circularly arranged cylinders or tubular chambers 11, said three cylinders being less than one-half of the total eight cylinders arranged circularly and peripherally with 80 in the frame 10, whereas the passage 22 extends about the openings of the remaining five cylinders or tubular chambers 11. It will also be noted that each shutter extends from the effective inner opening of said 85 passage 23 to a point within the said passage 22 for a distance greater than the diameter of a single cylinder or inner chamber 11. Accordingly, when the shutters 16 are rocked by handle 20 in the opposite direction, the effective inner opening is reduced 90 from five to three, thereby causing a reverse flow, the discharge 22 then becoming the inlet and inlet 23 then becoming the discharge. 95

24 is an arm rigidly mounted on lower rock shaft 17 and adapted to be pinned to the casing 3 by pin 25.

In the operation of the device assuming the inner chamber including the frame 10 105 to be driven clockwise, the uppermost set of plungers are shown as at the limit of their outstroke, the next set to the right just beginning the instroke, the next to the right a little farther on the instroke and so on, the 110 lowermost set of plungers being at the limit of the instroke, the next set to the left just

beginning the outstroke and so on, the water or fluid being sucked in as the plungers cross the inlet, carried past the lowermost shutter 16 and discharged as the plungers 5 pass the discharge, no water or fluid being able to return to the inlet because of the closure of shutters 16 against their respective shoulders 21. The shutter 16 having been shifted to the opposite position to that 10 shown and the direction of rotation of the inner chamber and frame 10 being reversed, the reverse operation is obvious, the water or other fluid in the now discharge end (formerly the inlet end) being incapable 15 of returning because of the closure of the shutters 16 against the casing 3 and the face of frame 10.

By the means described we are enabled 20 to obtain a greater pressure of air, steam or liquid with an expenditure of less power than heretofore and particularly because of the greater leverage gained by the relatively eccentric position of the shaft to the inner chamber, or frame, and casing.

25 It is obvious that the apparatus may be driven by the shaft instead of from a pulley on the wall of the inner chamber as shown, in which case the plate or socket 14 would be pinned to the shaft instead of rotating around the same and we do not restrict ourselves to the exact arrangement 30 shown, further than the scope of the appended claims demands, because the eccentric relationship is the important factor 35 whether the inner chamber or frame is driven directly by a belt or indirectly through the shaft.

We claim:

1. In a rotary pump, an outer casing, an 40 inner casing, a predetermined number of cylinders arranged peripherally within said inner casing, a shaft eccentric relative to

said inner casing, plungers disposed within said cylinders, connecting rods fastened at one end to said plungers and concentrically supported at the other end about said shaft, means for rotating said inner casing, a passage having an inner opening embracing a number of the openings of said cylinders less than one-half said predetermined 45 number of cylinders, a passage arranged oppositely to said passage and extending over the openings of the remainder of said cylinders and a movable element within said second named passage having a length greater 50 than the diameter of one of said cylinders. 55

2. In a rotary pump, an outer casing, an inner casing, a shaft disposed eccentrically relative to said inner casing, a socket on said shaft, a predetermined number of cylinders 60 arranged peripherally within said inner casing, a plurality of plungers disposed within said cylinders, connecting rods for the plungers fastened at one end to the respective plungers and fastened at the other end 65 to a common point on said socket, said connecting rods being arranged concentrically about said shaft, means for rotating said inner casing, a passage having an effective inner opening embracing a number of the openings of said cylinders less than one-half said predetermined number of cylinders, a passage arranged oppositely to said passage and extending over the openings of the remainder of said predetermined number of cylinders, oppositely arranged elements movable within said second named 70 passage each having a length greater than the diameter of one of said cylinders, and common means for operating said elements. 75 80

In testimony whereof we have signed this specification.

ANTONIO BORRÁS.
FERNANDO IRIARTE.
